CLAIM

The ornamental design for an indicator light module, as shown and described.

DESCRIPTION

FIG. 1 is a perspective view of an indicator light module, showing the module in an indicator light assembly.

FIG. 2 is a front elevational view of the indicator light module shown in FIG. 1.

FIG. 3 is a perspective view of the indicator light module shown in FIG. 1; and,

FIG. 4 is a front elevational view of the indicator light module shown in FIG. 3.

The broken line showing is included for the purpose of illustrating portions of the “article” and forms no part of the claimed design.
